UNITED STATES PATENT OFFICE.

SOLOMON ELDRED GILBERT, OF PHILADELPHIA, PENNSYLVANIA.

SADDLE FOR VELOCIPEDES.

SPECIFICATION forming part of Letters Patent No. 415,291, dated November 19, 1889.

Application filed August 28, 1889. Serial No. 322,227. (No model.)

To all whom it may concern:

Be it known that I, SOLOMON ELDRED GILBERT, a citizen of the United States, residing at Philadelphia, in the county of Philadelphia and State of Pennsylvania, have invented 5 certain new and useful Improvements in Saddles for Velocipedes, &c., of which the following is a specification.

In the use of bicycles and tricycles it has 10 been found desirable to provide the seat with as much elasticity as possible to relieve the motion of the machine in passing over the ground, and especially if the road be rough or uneven. As the support for the seat must 15 be comparatively rigid to bear the weight of the rider, I have invented an air-cushion to be secured to the saddle, or, rather, an air-saddle which can be secured directly to the machine, and by means of which the weight 20 of the rider is borne upon a cushion of air and the disagreeable effects of the jar of the machine are entirely avoided.

In adapting my air-cushions to the different machines I have found it best to mold a 25 leather base into any desired form, which may be secured to the machine in place of the saddles now in use, and have the air-cushions secured to that.

The construction will be more clearly understood by referring to the accompanying drawings, in which—

Figure 1 is a top plan view of my improved air-saddle. Fig. 2 is a longitudinal vertical sectional view of the same. Fig. 3 is a transverse sectional view on the line $x-x$ of Fig. 2, and Fig. 4 is a bottom plan view.

The base 1 of the saddle is formed of leather or other like material that can be softened and then molded into the desired shape, which 40 it will retain when it again becomes dry or hard. Extending almost entirely around the base, which is substantially pear-shaped in outline, is a downwardly-projecting reinforcing rim or flange 2, to which the edge of 45 the air-cushion 3 is secured by any suitable means, as by stitches 4, rivets, or by means of glue or cement. The base is attached or secured to the machine at the rear by the ordinary curved support 5, which is riveted to 50 the interior of the flange at that portion of the saddle, and which in turn is secured to the machine by the bolt 6, although different

machines will necessitate slight changes in the means of support at this point as well as in front. The front of the saddle, which I will 55 call the "horn," is almost semi-cylindrical in cross-section, and has a hook 7 secured near the end, the flange 2 being omitted at that point to permit of the hook engaging with the machine. The base is provided with a 60 concavity 8 in the larger portion, which will assist in relieving the jar or inconvenience experienced from jolts or quick movements of the machine.

The cushion for the saddle is composed of 65 two pieces 9 and 10, of any fine material that is impervious to air, as rubber-cloth, glazed leather, &c., and which are cut out in the same general shape as the base, but somewhat larger than it. These two pieces are then 70 secured together about an inch from their edges by cement or glue, which will thus give a margin 11 all around the cushion, by means of which it can be attached to the rim of the leather base, as hereinbefore described. This 75 construction permits of the air within the cushion extending all over the top of the saddle and entirely out to the outer edge of the saddle, and especially so upon the horn, when the cushion will afford support and relief for 80 the person of the rider and prevent the tired feeling experienced in other saddles. By making the base of molded leather I produce a saddle that will have the rigidity to retain 85 its actual shape and firmly support the air-cushion under the heaviest load and yet be sufficiently yielding to prevent any portions of it, and especially the flanges along the horn, from bearing against the rider hard enough 90 to chafe or injure him while riding.

If desired, the cushion and saddle may be made separable, so that the saddle can be used without the cushion and the cushion can be used upon other makes of saddle, although the best results will be obtained by securing 95 the two together, substantially as described above. The air-cushion can be filled in the usual manner by the valve 12 at one end, and the amount of air may be varied to suit the rider or the circumstances; and instead of removing the cushion from the saddle, the same result may be obtained by opening the valve and forcing all the air out of the cushion. Whenever the cushion becomes worn or de-

fective in any manner, it can be easily removed and a new one substituted in its place; and, as a mounted leather base can be manufactured almost if not entirely as cheaply as the ordinary saddles and has manifest advantages over them, as also over a metallic base, which would be too rigid and unyielding for comfort, it is evident that it is a decided improvement over those heretofore in use, and especially so when combined with my improved air-cushion.

Having thus described my invention, I claim—

1. As a new article of manufacture, a molded leather saddle for bicycles, &c., having a concavity in its larger portion and an air-cushion extending over the concavity and over the top of the seat, substantially as described.

2. The combination, with a saddle for bi-

cycles, of an air-cushion secured thereto, said cushion being formed of two pieces joined together at a distance from their edges, whereby it is provided with a margin, substantially as described.

3. The combination, with a bicycle-saddle provided with a downwardly-extending flange, of an air-cushion provided with a margin for securing it to the flange of the saddle, the concavity of the cushion extending entirely out to the outer edge of the saddle, substantially as described.

In testimony whereof I have signed my name to this specification in the presence of two subscribing witnesses.

SOLOMON ELDRED GILBERT.
